UNITED STATES PATENT OFFICE.

BECKER C. KNUDSEN, OF CLINTON, IOWA.

VEHICLE-CURTAIN-WINDOW STRUCTURE.

1,179,844.

Specification of Letters Patent. Patented Apr. 18, 1916.

Application filed March 31, 1915. Serial No. 18,309.

To all whom it may concern:

Be it known that I, BECKER C. KNUDSEN, a citizen of the United States, residing at Clinton, in the county of Clinton and State 5 of Iowa, have invented certain new and useful Improvements in Vehicle-Curtain-Window Structures, of which the following is a specification, reference being had therein to the accompanying drawing.

10 This invention relates to attachable window-structures and more especially to window-structures attachable in the sight-openings of vehicle curtains.

In automobiles having tops, there is 15 usually a sight-opening in the curtain at the rear. From one cause or another, this frequently becomes broken and is generally not replaceable except by removing the entire curtain, etc., because it is permanently 20 fitted therein. When broken or damaged, the curtain presents an unsightly appearance; but the owner of the car cannot usually remedy the defect except at considerable expense.

25 It is the object of my invention to provide an attachable and detachable window-structure of simple and inexpensive construction and of such character that it may be easily mounted in place without the use 30 of special tools and with great facility.

To this end, the invention resides in a curtain window-structure that may be manually secured in place and which includes a transparent element (preferably of flexible 35 material) to which is secured a border or edging-element provided with or carrying means adapted to secure the structure to the edges or margins of the sight-opening in the curtain. The structure may also include 40 a flap-element secured on one side of the transparent element along a line somewhat removed from the edge thereof whereby a sort of skirt or flap is presented and between which and the sheet the said curtain-margins 45 are attachably secured. The fastening means may be of any appropriate form.

This invention in general seeks to provide a structure of the kind described which is particularly adapted for application to 50 existing curtains wherein the window is damaged, or where it may be desired to provide a sight-opening. From a structural standpoint, it is of great simplicity and, operatively, it possesses the characteristics 55 of being durable and efficient.

The invention has other objects in view and is characterized by other advantages, as will be more apparent from the annexed drawings and the following description.

It resides broadly in the features of construction and in the related aggroupment of the different elements thereof, all as will be exemplified in the construction herein-after set forth, and the scope of application of which will be indicated in the appended 65 claims.

That the invention may be readily comprehended, drawings illustrating a possible embodiment and utilization of the same are hereto appended as a part of this disclosure, 70 it being manifest that other possible embodiments and utilizations (employing the underlying principles of the invention) fall within the spirit thereof and within the objects contemplated thereby. 75

In the accompanying drawings: Figure 1 is a view of a vehicle top with a curtain provided with my window-structure; Fig. 2 is a detached view of the structure, by itself; and Figs. 3 and 4 are fragmentary 80 views, in section, showing the details of the structure on a somewhat larger scale.

Referring to these drawings, the reference-character 1 designates, generally, a vehicle top. This is provided with a rear curtain 2 of any appropriate material and style. The curtain has a sight-opening 3. Ordinarily, this sight-opening contains a window more or less permanently secured therein. Hence, should it become damaged, 90 it is practically impossible for an unskilled person to replace the broken window by a new one. It is the aim of my invention to provide the curtain with a new window and one which can readily be applied by almost 95 anyone. This consists, preferably and as shown, of a sheet of transparent material 4—preferably celluloid, mica, or similar material, though glass may, if desired, be utilized—surrounded by means for attaching it to the margins of the sight-openings. These means, preferably and as shown, include the following instrumentalities: Sewed or otherwise secured along the edges of the transparent sheet or window 4 is a 105 border or edging element 5. In this instance, it is revealed as a flexible strip having a portion 6 turned over the edge of the sheet and stitched thereto, as shown. The opposite edge-portion 7 is preferably folded 110

over against itself and is also stitched as at 8, to the sheet. There are, therefore, two lines of stitching.

On the opposite side of the sheet is secured what I shall herein designate a "flap-element" 9. This is, preferably and as shown, a flexible strip or band which is stitched to the sheet at 10, that is, along a line somewhat removed from the edge of the sheet. This provides a free or flap-portion: and, between it and the surface of the sheet 4 there is presented a curtain-receiving space 11. Into this space, the edges and margins 12 of the sight-opening in the curtain 2 are inserted. The curtain, sheet, edging and flap are then fastened together by appropriate means. In practice, I have found that the means herein illustrated are well adapted for this purpose and such means contemplate the following: The edging, flap, etc., having been perforated (in any suitable manner) fastening-elements 13 are inserted into the perforations and their ends 14 clenched against an interposed washer 15. In this way, the curtain is clamped (so to speak) between the flap and window-sheet 4, while the edging protects the edge of the sheet.

To afford rigidity to the structure, I may, if desired, dispose a stiffening element 16, in the form of a wire (for example) in the edging; but this would ordinarily not be used where the curtain has to be folded or rolled though, even in this instance, it might be made in sections, and, thus, permit any desired or necessary rolling, etc.

When it is desired to apply my structure, a person may proceed as follows: In the first place, the fragments and pieces of the broken window should be removed. Then, if the sight-opening is of proper dimension to receive my structure—or, if not, it is quickly made so—said structure is placed in position: To this end, the fastening elements having first been removed from the structure, the edges and margins are carefully inserted into the space 11. Then, the flap is pressed against it and the fastening elements reinserted and made to extend through the curtain margins and clenched.

The edging, which forms a frame, may if desired, be of stiff material and, in fact, may be of metal, in which instance, I could place two of the frames at opposite sides of the transparent sheet and secured thereto and

to each other in clamped relation. Usually, however, the edging would be made of leather, oil-cloth, or other fabric.

From the foregoing, it will be perceived that I have devised, as an article of manufacture, a manually-insertible curtain-window structure, preferably flexible in character, and including means for securing it in the sight-opening of a vehicle or other form of curtain. It is exceedingly simple and compact in form, it is conveniently applied without the use of tools, and it is of attractive appearance.

It is to be understood that all matter contained in the foregoing description and shown in the accompanying drawings is intended to be illustrative merely and that the invention is susceptible of a wide range of modification without a departure from its spirit.

What I claim is:

1. An attachable curtain window comprising a sheet of flexible and transparent material; a flexible border-element secured around the edges of the sheet on one side thereof; and a flap, composed of flexible material, secured in proximity to the edges of the sheet on the opposite side thereof, to constitute with said sheet and border-element, a pocket for the reception of the edges of a sight-opening in a curtain.

2. In combination with a curtain having a sight opening provided with perforate edges; a window structure therefor comprising a flexible transparent member; a border secured around the edges of one side thereof; a flap secured around the edges on the side opposite said border, to constitute with said border and window, a pocket for the reception of the edges of the sight opening in the curtain; said curtain, border, window and flap being provided with perforations adapted to register with the perforations in the curtain when the edges of the curtain around the sight opening are disposed in the pocket; and a plurality of fastening elements adapted to be disposed in said perforations to secure the parts together.

In testimony whereof I affix my signature in presence of two witnesses.

BECKER C. KNUDSEN.
